(57) **CLAIM**

The ornamental design for monthly pill container with locking lids, as shown and described.

DESCRIPTION

FIG. 1 is a front view of the monthly pill container with locking lids according to the present invention, the container including seven rows of five openings, a sliding lid being associated with each row of openings;

FIG. 2 is a top view thereof;

FIG. 3 is a bottom view thereof;

FIG. 4 is a right side view thereof;

FIG. 5 is a left side view thereof;

FIG. 6 is a front view thereof with a lid of the container in a partially slid open position to provide viewing an opening associated with the lid;

FIG. 7 is a right side view of the container shown in FIG. 6; and,

FIG. 8 is a left side view of the container shown in FIG. 1 with a sliding side door of the container in a partially open position.

Applicant disclaims details that would otherwise be shown in a back view of the container.

The broken line showing of environment in the drawings if for illustrative purposes only and forms no part of the claimed design.
